UNITED STATES PATENT OFFICE.

RUDOLPH ROBERT BUEHLER, OF PHILADELPHIA, PENNSYLVANIA.

GONG DOOR-BELL.

SPECIFICATION forming part of Letters Patent No. 324,915, dated August 25, 1885.

Application filed April 27, 1885. (No model.)

To all whom it may concern:

Be it known that I, RUDOLPH ROBERT BUEHLER, a citizen of the United States, residing at Philadelphia, in the county of Philadelphia and State of Pennsylvania, have invented certain new and useful Improvements in Door-Bells or Gongs; and I do hereby declare the following to be a full, clear, and exact description of the invention, reference being had to the accompanying drawings, which form part of this specification, in which—

Figure 1 is an elevation, the gong being shown in dotted lines. Fig. 2 is a perspective of hammer-plate. Fig. 3 is a detail perspective of pull-lever inverted.

My invention has relation to double-stroke door-bells, and my improvements have for their object to provide a construction which will insure a second or return stroke of the hammer with as much certainty and force as the first stroke. In double-stroke bells, as heretofore constructed, there has been a tendency to miss on the return or back stroke or to make a fainter stroke than on the forward movement, owing to the fact that the bell-handle will frequently be held onto and allowed to return slowly by the person ringing after pulling said handle, instead of letting go completely of the same. By my invention there is provided a construction which will produce a quick, firm, and decided stroke on the back-stroke of the hammer, as well as on the forward stroke, no matter how slowly the bell-handle be allowed to return to its normal position.

My improvements consist in the peculiar construction and combinations of parts hereinafter described and specifically claimed, having reference principally to the combination, with the bell-hammer and lever for moving the same, of an intermediate plate, to which said hammer is secured and with which said lever engages, and a spring attached by its ends to said plate and the base-plate or bracket of the bell, respectively, as hereinafter set forth.

Referring to the accompanying drawings, A indicates the bracket or base-plate having a post, B, on which the bell or gong C is mounted in the usual or any suitable manner.

D is the bell-hammer, and E the lever by which the same is operated, said lever having holes e e e for the attachment of the bell-wire,

whose other end is to be secured to a proper handle or pull.

G is the check or retracting spring, one end of which is secured to a post, a, on the base-plate A, the other end engaging with one of the hooks e' e'' on said lever. Two or more of these hooks are provided for adjusting purposes and to regulate the tension of the check-spring.

The hammer D is secured to plate F, which is swiveled on a pintle, H, on which the lever E is also pivoted, said pintle entering an opening in a boss, a', on the base-plate A. The movement of the lever E and plate F on their pintle H is limited by a projection, a'', arising from the base-plate A, the shoulders e'' e''' and f' f'' on said lever E and plate F, respectively, abutting alternately against the edges of said projection when said lever and the hammer are moved. The plate F has on its upper side a stud or projection, f'', which enters a segmental recess, e'', in the under side of lever E, and has play-space between the shoulders or ends e'' e''' of recess.

I is a coiled spring, with its ends prolonged and bent, the end i entering an opening in the base-plate A, and the other end, i', entering an opening, f''' in the plate F. The center of movement of this spring is its end i, and it is in a state of tension or compression when a line drawn through its ends passes through the middle of post B and pintle H, or when in the position shown in dotted lines in Fig. 1. As it passes this center line its tendency is to throw forward the hammer D and plate F in the direction of its movement, whichever way that direction be, either forward or backward. Its normal position is to one side of the center, or, as shown in Fig. 1, to the left of the pintle H. Now, on pulling the lever E in the direction of the arrow and against the force of the check-spring G, the shoulder e'' of recess e'' bears against the stud f'' on the plate F and causes said plate to turn on the pintle H, carrying the hammer forwardly and compressing or producing tension in spring I. The instant the end i' of spring I passes the center line described it finds relief by moving the plate F until its stud f''' meets the shoulder e''' of recess e'', thus giving the forward stroke of the hammer. On the return motion of the lever, due to the tension or retractile exertion of the

check-spring G, the shoulder e^7 bears against projection f^2 and moves the plate F backwardly, causing spring I to again cross the described center line, but in the reverse direction from what it did before. As it passes said center it throws the plate F, and with it the hammer D, in the direction of its movement—that is, backwardly—thus giving the back-stroke, the projection f^2 moving from shoulder e^7 to shoulder e^6 . As this action of the spring I occurs whenever it passes its center, as described, it follows that, no matter how slowly the lever be moved, either forwardly or backwardly, the hammer will give a quick and firm stroke and that two strokes will be made for every oscillation of the lever or each pull of the bell-handle.

15 What I claim as my invention is as follows:

1. In a bell-stroke movement, the combination, with lever E, having shoulders e^6 e^7 , of 20 plate F, having projection f^2 , and spring I, substantially as shown and described.

2. The combination, with base-plate or bracket A, of hammer D, lever E, having shoulders e^6 e^7 , plate F, having projection f^2 , 25 pintle H, check-spring G, and stroke-spring I, said several parts being combined and constructed for operation substantially as shown and described.

In testimony that I claim the foregoing I 30 have hereunto set my hand this 23d day of April, 1885.

RUDOLPH ROBERT BUEHLER.
